N.Y. 11803

Filed June 5, 1963, Ser. No. 285,632
12 Claims. (Cl. 323—22)

This invention relates to open loop stabilized sources of direct current and potential for use as D.C. power supplies and as reference sources in power supplies and other equipment.

There are presently known to the art a wide variety of vacuum tube and solid-state constant current and potential sources ranging from simple zener diode circuits to series and shunt regulators employing an externally closed and basically degenerative loop. The complexity of the circuit varies somewhat in relation to operating requirements, general purpose and high capacity supplies being considerably more complex than fixed purpose or low power sources.

Circuit complexity is also a function of the required degree of constancy or regulation in the presence of temperature, line and load fluctuations. Where a simple zener diode circuit, with or without a transistor to form a constant current amplifier cannot meet these requirements, it is generally the practice to employ closed loop series or shunt regulators. The latter, besides being complex and expensive per se, are generally prone to instability problems requiring added complexity and expense by way of stabilizing schemes.

It is thus an object of the invention to provide a source of constant voltage or current which preserves the open loop simplicity of simple circuit sources while providing regulation and stability not otherwise attainable in such circuits.

These and other objects and advantages of the invention will be set forth in part hereinafter and in part will be obvious herefrom or may be learned by practice with the invention, the same being realized and attained by means of the instrumentalities, combinations, and improvements pointed out in the appended claims.

The invention consists in the novel parts, constructions, arrangements, combinations and improvements herein shown and described.

Serving to illustrate an exemplary embodiment of the invention is the sole figure illustrating in schematic form a circuit adapted to supply a plurality of stabilized D.C. outputs.

As seen in the figure, an A.C. potential is developed across the secondary winding SW_2 of a transformer T_1 which is energized from a primary winding P_1 . The primary is excited via a power switch S_1 from an alternating current source. The potential across the secondary is converted to a unidirectional voltage, illustratively by means of a full wave circuit which includes rectifiers CR_{16} and CR_{17} in full wave configuration; the circuit also includes a filter capacitor C_7 . The relatively unregulated D.C. voltage appearing across capacitor C_7 is connected to and appears across output terminals E_1 and E_7 which may supply a circuit not requiring a regulated output.

Energized by the potential E_1-E_7 are two branches R_{27} , CR_{15} and R_{28} , R_{26} . CR_{15} is a forwardly conducting silicon junction diode utilized for reasons hereinafter noted. The branches R_{27} , CR_{15} and R_{28} , R_{26} supply energizing potential for a transistor Q_8 . Thus the base of transistor Q_8 is connected to the junction of R_{27} and CR_{15} while the emitter thereof connects to the junction of R_{28} and R_{26} . With this circuit arrangement, the voltage across R_{26} tends to equal the somewhat constant voltage across CR_{15} . Hence the emitter current,

2

and therefore the collector current, of Q_8 tends to be constant. The use of CR_{15} instead of a zener diode has the advantage in this circuit of providing a measure of ambient temperature compensation since the thermal characteristics of CR_{15} tend to compensate for the similar characteristics in the base-emitter junction of Q_8 .

The effect of the connection which includes R_{28} is to introduce into the base-emitter of Q_8 , a corrective signal which compensates for the fact that the impedance of CR_{15} , although relatively low is not zero whence line voltage fluctuations appear in attenuated form in the emitter-base circuit of Q_8 unless this compensation is provided. The effect of this connection also functions to minimize temperature fluctuations in Q_8 resulting from E_1-E_7 voltage variations and not compensated by CR_{15} . Proportioning of R_{26} and R_{28} may also be utilized to provide over-compensation. The overall circuit thus far described is thus seen to provide a relatively stable, substantially constant current in the collector of Q_8 .

It may be observed that the circuit thus far described appears topographically similar to conventional error detector stages in many closed loop regulators. In such stages there is frequently provided a voltage reference branch and an output sampling branch to which are connected the emitter-base circuit of an error detecting transistor. However, in these arrangements the elements are chosen so that the emitter-base potential, and thus the emitter-collector current, varies in accordance with output voltage fluctuations. In contradiction, the circuit herein described is designed to do the very opposite, i.e., maintain the emitter-base potential and emitter-collector current constant in spite of variations in the supply voltage.

The constant collector current in Q_8 also flows in the reverse current direction through CR_{11} , preferably a temperature compensated zener diode, and also through CR_{12} , these elements being in series and connected in a branch from the collector of Q_8 to terminal E_1 ; this branch also includes R_{25} in serial relation and the series-parallel network CR_{13} , CR_{14} and R_{29} . The constant current through zener diode CR_{11} supplements the inherently and relatively constant voltage characteristic of the zener diode, thereby providing a constant voltage across CR_{11} which has stability improved over that provided by conventional zener diode circuits and so called "constant current circuits."

Energized by the collector output of stage Q_8 is a further stage Q_6 in emitter-follower relationship. The emitter-base circuit of this stage is temperature stabilized with the aid of CR_{12} , the ambient thermal characteristics of which tend to offset the similar characteristics in the base-emitter junction of Q_6 .

The stabilized emitter-current of stage Q_6 flows from E_1 through the combination R_{29} , CR_{14} , CR_{13} , in part through zener diode CR_4 and resistor R_6 and in part through a branch paralleling CR_4 and R_6 and comprising R_{14} , R_{13} , R_{15} and R_{16} , the first and last-mentioned being conveniently variable. These branches, in response to the emitter-current of Q_6 produce highly stabilized voltages, especially the voltage E_3-E_4 dropped across CR_4 .

As previously noted, temperature stability of the base-emitter of Q_6 is aided by the presence of CR_{12} which has similar thermal characteristics. However, in maintaining a constant current in its emitter circuit, the emitter-collector voltage of Q_6 will tend to vary in the presence of disturbances. As a consequence, the power dissipation of Q_6 will tend to vary causing a related change in the thermal characteristics of Q_6 which would not fully be compensated by CR_{12} .

To overcome this difficulty, there is connected across the emitter-collector of Q_6 , the base-emitter circuit of a

further stage Q_7 . The collector of Q_7 is returned through R_{23} to E_1 ; the emitter is connected to E_7 via R_{24} which is also common to the emitter Q_6 .

The tendency of the emitter-collector potential of Q_6 to change is thus counteracted by the corrective action of Q_7 . A tendency toward voltage change in the emitter-collector of Q_6 produces a change in the emitter-current of Q_7 , thus producing a voltage change across R_{24} which tends to offset the assumed change in Q_6 .

Transistors Q_6 and Q_7 are of opposite conductivity type; further Q_6 and Q_7 are preferably germanium and silicon types, respectively, although Q_7 may be germanium provided an extra diode is added to the circuit. By this arrangement, the operation of both transistors within their correct dynamic range is assured.

The emitter-current of Q_6 is thus seen to be a highly stabilized parameter which may be used per se as a current source and which also produces correspondingly stabilized output potentials E_3-E_4 , E_3-E_c , and E_c-E_5 . The latter two are conveniently adjustable by varying R_{14} 20 and R_{16} .

Other potentials may also be provided, such as E_1-E_2 , E_2-E_3 , E_1-E_5 , E_3-E_7 , E_4-E_5 , and other combinations. The use of these potentials in a general purpose closed loop supply is illustrated in a copending application assigned to the assignee of the instant application, filed June 5, 1963, and having Ser. No. 285,780, and of which the applicants herein are co-inventors.

The invention is not limited to the specific combinations, arrangements and elements herein shown and described as the art will recognize modifications thereof. Departures may thus be made from the foregoing without departing from the principles of the invention and without sacrificing its chief advantages.

What is claimed is:

1. A substantially constant D.C. source comprising a source of unregulated D.C. energy,

a transistor including a base, emitter and collector; circuit means connected across the emitter-base circuit of said transistor including

a diode means having thermal characteristics related to the thermal characteristics of the emitter-base junction of said transistor for supplying a reference potential to the emitter-base circuit of said transistor, and resistance connected to said diode means for providing a potential which compensates for the variations in said reference potential due to the dynamic impedance of said diode means;

a first circuit branch means connected across said source and including said diode means to energize said diode means and develop said reference potential;

a second circuit branch means connected across said source and including said resistance for developing said compensating potential as a function of the potential across said source; and

a third circuit branch means connected across said source and including the emitter-collector circuit of said transistor, said third circuit branch being characterized by a substantially constant current flow therethrough.

2. A substantially constant D.C. source in accordance with claim 1 wherein said diode means is selected having a temperature coefficient essentially the same as the temperature coefficient of the emitter-base junction of said transistor, wherein said diode means is energized to provide said reference potential while operating in its forward conducting region, and wherein said diode means is so connected that said reference potential is in opposition to the potential developed across the emitter-base junction of said transistor.

3. A substantially constant voltage source comprising a substantially constant current source in accordance with claim 1 and a Zener diode connected in said third circuit

branch means in series with the collector of said transistor, said Zener diode being connected to operate in its Zener region to thereby provide a substantially constant voltage across said Zener diode.

5. A substantially constant D.C. source comprising a source of unregulated D.C. energy,

a transistor including a base, emitter and collector; circuit means connected across the emitter-base circuit of said transistor including

a diode having thermal characteristics related to the thermal characteristics of the emitter-base junction of said transistor for supplying a reference potential to the emitter-base circuit of said transistor, and

a resistance connected in series with said diode for providing a potential which compensates for the variations in said reference potential due to the dynamic impedance of said diode, and which compensates for thermal differences between said diode and said junction,

said diode and said resistance being connected in series between the emitter and base of said transistor so that the net emitter-base potential is substantially stabilized notwithstanding temperature and source voltage changes;

a first circuit branch means connected across said source and including said diode to energize said diode and develop said reference potential;

a second circuit branch means connected across said source and including said resistance for developing said compensating potential as a function of the potential across said source; and

a third circuit branch means connected across said source and including the emitter-collector circuit of said transistor, said third circuit branch being characterized by a substantially constant current flow therethrough;

a second transistor including an emitter, base and collector;

circuit means for temperature stabilizing said second transistor;

the emitter-base circuit of said second transistor being in said third circuit branch means and coupled to the collector of said first transistor, and

circuit means connected to the collector-emitter circuit of said second transistor to provide a substantially constant D.C. output.

5. A substantially constant D.C. source in accordance with claim 4 wherein said diode is selected having a temperature coefficient essentially the same as the temperature coefficient of the emitter-base junction of said first transistor, wherein said diode is energized to provide said reference potential while operating in its forward conducting region, and wherein said diode is so connected that said reference potential is in opposition to the potential developed across the emitter-base junction of said first transistor.

6. A substantially constant D.C. source in accordance with claim 4 further including a Zener diode connected in said third circuit branch means to provide a constant potential at the base of said second transistor.

7. A substantially constant D.C. source in accordance with claim 4 further including additional circuit means connected to the emitter-collector circuit of said second transistor to maintain a substantially constant potential across said emitter-collector circuit of said second transistor.

8. A substantially constant D.C. source in accordance with claim 7 wherein said additional circuit means includes

70 a third transistor including an emitter, base and collector, the emitter-base circuit of said third transistor being connected across the emitter-collector circuit of said second transistor, a common resistor connected in series with the emitter-collector circuits of said second and third transistors.

9. A source as defined in claim 8 in which said second and third transistors are of opposite conductivity type and are silicon and germanium types, respectively.

10. A substantially constant D.C. source in accordance with claim 6 further including a Zener diode connected 5 in said third circuit branch means to provide a constant potential at the emitter of said second transistor.

11. A substantially constant D.C. source comprising a source of unregulated D.C. energy, 10 a transistor including a base, emitter and collector; circuit means connected across the emitter-base circuit of said transistor including

a diode having thermal characteristics related to the thermal characteristics of the emitter-base junction of said transistor for supplying a reference potential to the emitter-base circuit of 15 said transistor, and

a resistance connected in series with said diode for providing a potential which compensates for the variations in said reference potential due to the dynamic impedance of said diode, and which compensates for thermal differences between 20 said diode and said junction,

said diode and said resistance being connected in 25 series between the emitter and base of said transistor so that the net emitter-base potential is substantially stabilized notwithstanding temperature and source voltage changes;

a first circuit branch means connected across said 30 source and including said diode to energize said diode and develop said reference potential;

a second circuit branch means connected across said source and including said resistance for developing 35 said compensating potential as a function of the potential across said source;

a third circuit branch means connected across said source and including the emitter-collector circuit of said transistor, said third circuit branch being characterized by a substantially constant current flow therethrough;

a second transistor including an emitter, base and collector;

a diode having temperature characteristics related to the temperature characteristics of said second transistor connected in series with the emitter base circuit of said second transistor to provide temperature stabilization;

circuit means connected across the collector-emitter circuit of said second transistor to maintain substantially constant potential thereacross; and

an output circuit including the emitter-collector circuit of said second transistor for providing a substantially constant D.C. output.

12. A substantially constant D.C. source in accordance with claim 11 further including a Zener diode connected in said output circuit in series with the emitter-collector circuit of said second transistor.
